J. WINKLE.

Moulding Crucibles.

No 85,775.

Patented Jan. 12, 1869.

Inventor;

Joseph Winkle

JOSEPH WINKLE, OF PITTSBURG, PENNSYLVANIA.

Letters Patent No. 85,775, dated January 12, 1869.

IMPROVEMENT IN MACHINES FOR MAKING CRUCIBLES.

The Schedule referred to in these Letters Patent and making part of the same.

To all whom it may concern:

Be it known that I, JOSEPH WINKLE, of Pittsburg, in the county of Allegheny, and State of Pennsylvania, have invented a new and useful Improvement in Machines for Making Crucibles; and I do hereby declare that the following is a full and exact description thereof, reference being had to the accompanying drawings, and to the letters and figures of reference marked thereon.

The nature of my invention consists in providing a machine for moulding crucibles with a jointed lever, to which is attached a forming-blade, so arranged, with relation to said jointed lever, and the mould in which the crucible is formed, that said forming-blade will enter the centre of the mass of clay for forming the crucible, and force and spread it out against all sides of the inner wall of the mould, said forming-blade and its lever being so arranged that the forming-blade can be removed from the mould and formed crucible without displacing the forming-blade.

To enable others skilled in the art to make and use my invention, I will proceed to describe its construction and operation.

In the accompanying drawings, which form part of my specification—

Figure 1 is a side elevation of my improvement in machines for forming crucibles, representing a vertical section of the crucible-mould and its "chuck;" also the position of the forming-blade, while forcing the clay out against the walls of the mould.

Figure 2 is a side elevation of the machine, representing a vertical section of the mould and crucible, and the position of the several parts when removing the forming-blade from the formed crucible and its mould.

Figure 3 represents my improvement for removing the crucible from the lower part of the mould.

Figure 4 is a side elevation of the crucible-mould.

In the drawings—

A represents the frame of the machine, which is provided with uprights B and B'.

To the upright, B, at 3, is pivoted the part C of the jointed lever.

The part C' of the lever moves in a slot in the upright, B'.

To the part C' of the lever is attached a cord, g, which passes up and over a pulley in the upper end of the upright, B.

On the end of the cord is a weight, f.

The parts C' and C of the jointed levers are connected together by means of a hinge, D, provided with a guide, 1.

To the knuckle of the hinge is attached a cord, h, the lower end of which is attached to an arm, pivoted at x, and used for shifting the belt used for imparting motion to the mould-chuck l on the end of the shaft m, provided with a driving-pulley, o, and loose pulley, n.

To the arm i is pivoted a foot-lever, J, which is used for bringing the desired pressure on the jointed lever C and C', through the medium of which the forming-blade e forces the material, of which the crucible or other vessel is made, against the inner walls of the mould R, which is made in two parts, as shown in the accompanying drawings.

The bottom, w, of the mould R is detached, which is of great advantage for removing the pot from its mould.

To the part C of the jointed lever may be attached a cord for supporting it, as indicated at 2. This cord may also be provided with a weight to act as a balance to the jointed lever.

As the construction and arrangement of my improvement, and the relation the several parts bear to each other, will be readily seen and understood by the skilful mechanic, from the foregoing description, and by reference to the accompanying drawings, I will therefore, without further description of its construction, proceed at once to describe its operation, which is as follows:

The mould R is placed in the chuck l. I then weigh a suitable mass of the material to make a crucible. This mass is then placed in the mould R. The operator then places his foot on the lever J, which will draw down the jointed lever C and C', which will set the chuck in motion and bring the forming-blade e down into the centre of the mass, for forming the crucible, (as shown in fig. 1,) and force it out against all sides of the walls of the mould, and the blade e will keep on approaching one side of the mould until ends 4 and 5 of the jointed lever C and C' meet, at which time the crucible will be properly formed. The operator then removes his foot off the lever J, and the weight f, through the medium of the cord g, will raise up the jointed lever C and C', and thereby withdraw the forming-blade e out of the formed crucible, the operator guiding the lever and blade in their upward motion.

It will be observed that arm i and foot-lever J act in connection; that is to say, when the foot-lever J is pressed down, the arm i will shift the belt for operating the chuck on the driving-pulley o, and when the operator removes his foot off the lever J, it will rise up, and the arm i will shift the belt on to the loose pulley n, and the revolving motion of the chuck l will cease.

The mould R is then removed from the chuck, and, after the crucible is sufficiently dry, the upper part of the mould is removed, and the lower part is then placed with its bottom, w, resting on the upper end of the pedestal 6, and the other part of the mould is lower, leaving the formed crucible resting on the bottom, w, and pedestal 6, as shown in fig. 3.

The advantages of this arrangement for removing the formed crucible from its mould will be very apparent to all skilled in the art of moulding crucibles.

The mould R is made of "plaster Paris" or like material. The advantage of moulds made of this material consists in its power of absorbing the water and moisture from the formed crucible, thereby causing it to more readily leave the mould, which is a very desirable thing in moulding crucibles.

Having thus described the nature, construction, operation, and advantages of my improvement,

What I claim as of my invention, is—

The arrangement, herein described, of the jointed lever C' C, hinge D, forming-blade e, cords g and k, weight f, foot-lever J, belt-shifting arm i, and pulleys o and n, constructed and operated substantially as described, and for the purpose set forth.

JOSEPH WINKLE.
